(57) **CLAIM**

The ornamental design for a blender container, as shown and described.

DESCRIPTION

FIG. 1 is a perspective view of a blender container, in accordance with the present invention.

FIG. 2 is a front view of the blender container, as shown in FIG. 1.

FIG. 3 is a side view of the blender container, as shown in FIG. 1.

FIG. 4 is an opposing side view of the blender container, as shown in FIG. 1.

FIG. 5 is a rear view of the blender container, as shown in FIG. 1.

FIG. 6 is a top view of the blender container, as shown in FIG. 1.

FIG. 7 is a bottom view of the blender container, as shown in FIG. 1.

FIG. 8 is an exploded perspective view of the blender container, as shown in FIG. 1.

FIG. 9 is a perspective view of a second embodiment of the blender container of FIG. 1; and,

FIG. 10 is a perspective view of a blender container of FIG. 1, as shown with a central knob.

Any broken lines, shown throughout in the drawing figures, are included for the purpose of illustrating environmental structures only and form no part of the claimed design. Reference photographs are herein included for the purpose of illustrating structures shown in the drawing figures and are not intended, in any way, to limit the claimed design.
